UNITED STATES PATENT OFFICE

JOHN WESLEY MARDEN, OF EAST ORANGE, NEW JERSEY, ASSIGNOR TO WESTINGHOUSE LAMP COMPANY, A CORPORATION OF PENNSYLVANIA

INTRODUCTION OF ALKALI METALS INTO EVACUATED CONTAINERS

No Drawing.

Application filed March 20, 1926. Serial No. 96,335.

This invention relates to the introduction of chemically active metals into evacuated or gas-filled containers, such as electron discharge devices, and more particularly to the 5 introduction of alkali metals into such devices.

In the manufacture of electric devices it is desirable to introduce therein, a small quantity of an active substance in a pure state, 10 such as an alkali metal for the purpose of cleaning up residual gases in evacuated containers, purifying rare gases in gas-filled containers, activating the filament by increasing the electron emissivity thereof, lowering the 15 starting and operating potential of discharge lamps, rectifiers, etc., creating a residual metallic vapor in the envelope and for various other purposes.

Extreme difficulty has hitherto been experienced in attempting to introduce these highly volatile materials, particularly the alkali metals, such as caesium, potassium, sodium, etc., into the envelopes of various gas tight containers, since in their free state, these 25 metals combine very readily with the elements of the atmosphere and therefore cannot be handled to any extent.

The alkali metals caesium, potassium, sodium, lithium and rubidium, vaporize at 30 relatively low temperatures and if they are introduced in such devices prior to evacuation thereof, it is difficult to maintain them in a non-volatile state while baking out the envelope during the exhaust operation. 35 Heretofore, the alkali metals have usually been introduced into the envelope after exhausting by vaporizing the same from a side tube or container.

Hitherto, it has been proposed to introduce 40 volatile metals into evacuated containers in the form of a reducible compound which is subsequently reduced by means of a suitable reducing agent in order to liberate the alkali metal in the container. Such a method of 45 introducing alkali metals is described in co-pending application Serial No. 8,865 of Duncan MacRae, filed February 13, 1925, and entitled Introduction of alkali metals.

According to the above application, a com- 50 pound, such as a silicate, hydroxide or car-

bonate of the metal, is mixed with a reducing agent and applied with a suitable binder to a metallic part of the device which is adapted to be heated, as by high frequency induction, to effect the reduction of the compound. 55 While this process produces good results there is danger of these substances absorbing water vapor prior to their introduction into the device which is liberated at the time the decomposition takes place and deleteriously 60 effects the operation of the device in which the alkali metal is introduced. For instance, in electron discharge devices employing thoriated tungsten cathodes, the water vapor causes oxidation of the thorium content of 65 the cathode, destroying or seriously impairing its emission. It has not been possible to heat these compounds, in baking the device sufficiently to eliminate all the water therefrom. 70

In the manufacture of high vacuum devices it is the usual practice to bake the electrodes in hydrogen prior to mounting to remove all traces of oxygen therefrom and during evacuation, and to bake out the envelope 75 at relatively high temperatures to drive out all water vapor and occluded gases from the glass. It will be readily appreciated that it is useless to take these extreme precautions to eliminate all moisture from the device and 80 to again liberate water vapor after the tube has been sealed off by the decomposition of the alkali metal compounds.

It is one of the objects of the present invention to provide a practical method of introducing highly volatile metals, such as the alkali metal, into gas tight containers in a pure state, without the simultaneous introduction of water vapor. 85

Another object is to provide a method of introducing chemically active metals into evacuated containers in a non-hygrosopic condition and free from deleterious substances. 90

Another object is to provide an improved method of introducing alkali metal compounds into gas tight containers and liberating the alkali metal by reduction of the compound. 95 100

Other objects and advantages will herein-after appear.

In accordance with this invention the chemically active metal, which it is desired to employ in the evacuated device, is introduced into the device in the form of a stable moisture free or anhydrous compound which is subsequently reduced to liberate the metal in pure form and free from water vapor or other substance which might deleteriously effect the operation or life of the device. The stable compound may be mixed in powdered form with a finely divided reducing agent, such as magnesium or aluminum and applied with a suitable binder to an interior portion of the device, capable of being heated to a sufficient temperature to effect the reduction of the compound.

If desired, the compound and reducing agent may be enclosed in a capsule such as that described in my copending application Serial No. 745,071, filed October 22, 1924, entitled Introduction of vaporizable material into exhausted containers, and assigned to the Westinghouse Lamp Company. Briefly, such method consists in enclosing the compound in a metal tube of low melting point which is drawn to small size and cut into short lengths to form capsules containing a definite quantity of the material. The capsule may be welded or otherwise secured to a metal part of the device where it can be heated by high frequency induction currents to melt the capsule and liberate the contents.

The compounds which I prefer to employ are the double halide salts such as potassium-zirconium fluoride or caesium-uranium or zirconium fluoride, although the invention is not limited to any particular stable non-hygroscopic compounds since I have found that very satisfactory results can be obtained employing the permanganate, chromate or bichromate of the alkali metal. These latter compounds can be dried completely free of water and are easily prepared.

The double halide salts in powdered form may be mixed with a reducing agent such as magnesium or aluminum in molecular proportions or with an excess of reducing material and applied to the interior part of the device in any desired manner, where it may be subsequently heated to effect a reaction. The magnesium or aluminum combines with the halide forming magnesium halide and liberating the alkali metal. When employing an alkali metal permanganate, such as caesium permanganate, I prefer to use a gentle reducing agent, such as powdered iron or nickel instead of aluminum and magnesium, since the permanganate contains a large quantity of oxygen and with powerful reducing agents, gives a vigorous reaction.

In the production of alkali metal radio tubes, such as caesium amplifier tubes which employ a tungsten filament, the combination

of caesium permanganate or caesium bichromate and a metallic reducing agent, such as iron or aluminum, may render it possible to supply the oxygen for oxidizing a tungsten filament as well as supplying the caesium by one single heating process. In making caesium amplifier tubes at the present time, it is customary to thoroughly exhaust and bake out the tube and then to admit a small amount of oxygen therein from an outside container. The filament is flashed in the oxygen to oxidize the surface thereof to render it capable of retaining a film of caesium metal thereon. The excess oxygen is then pumped out and the caesium introduced into the device. By employing caesium permanganate or bichromate or other oxygen-containing compound of the alkali metal, the step of introducing oxygen from a separate source may be eliminated and the oxygen supplied by the decomposition of the compound.

While a number of specific stable non-hygroscopic and moisture-free compounds have been specified herein, it is to be understood that the invention is not limited to the compounds or reducing agents mentioned, but that the invention contemplates the use of all equivalent compounds which may be reducible either by heat alone or by other reducing agents. In place of aluminum and magnesium, misch metal may be employed for reducing the compound. Calcium metal may also be used, although the other reducing agents mentioned are preferred since calcium forms hydroxides and carbonates in the air and therefore, admits of the possibility of introducing some water vapor or other deleterious material into the envelope.

It is understood that many modifications may be made in the invention described herein without departing therefrom and I do not desire to be limited to the exact embodiments described.

What is claimed is:

1. The method of introducing caesium into an evacuated container which comprises introducing caesium-uranium fluoride mixed with magnesium into the container and heating the mixture to liberate the caesium.

2. A getter for an electric discharge device comprising a non-hygroscopic compound of caesium mixed with magnesium.

In testimony whereof, I have hereunto subscribed my name this 18th day of March, 1926.

JOHN WESLEY MARDEN.
